To all whom it may concern:

Be it known that I, CHARLES F. SCHRADER, a citizen of the United States, residing in Philadelphia, Pennsylvania, have invented a certain Design for an Atomizer-Top, of which the following is a specification.

My design for an atomizer top is fully shown in the accompanying drawings, in which—

Figure 1, is a perspective view of the top; 10 and Fig. 2, is a side view of the same.

The essential features of my design are the cylindrical lower portion of the top, the upper conical portion with the two projections extending from each side of the said conical 15 portion, upwardly and outwardly at about the same angle therefrom.

a is the cylindrical lower portion and *d*, is the conical upper portion.

f, and *g*, are the two projections at each side of the conical top, each of which has a rounded surface, the projection, *f*, being of general conical shape and *g*, of general cylindrical shape.

I claim—

The design for an atomizer top, substantially as described and as shown in the accompanying drawings.

In testimony whereof I have signed my name to this specification in the presence of two subscribing witnesses.
